UNITED STATES PATENT OFFICE.

SAMUEL B. McHENRY, OF BLOOMSBURG, PENNSYLVANIA.

BRUSH.

1,306,308.

Specification of Letters Patent. Patented June 10, 1919.

Application filed June 18, 1918. Serial No. 240,587.

To all whom it may concern:

Be it known that I, SAMUEL B. McHENRY, a citizen of the United States, residing at Bloomsburg, in the county of Columbia and State of Pennsylvania, have invented certain new and useful Improvements in Brushes; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 This invention relates to brushes, but more particularly to a street broom or brush in which a heavy, stiff fiber is employed.

The invention has for its object to provide improvements in brushes of the aforementioned type, so that a more perfect article is obtained.

It has been difficult to construct brushes of this type having the fiber full at the ends so that the ends of the brush are effective.

25 This invention consists in a construction which insures the proper distribution of the fiber at the ends, so that the fiber will be permanently secured to the brush and against displacement and dropping out. The invention also consists in the ferrule arrangement for the handle, so that the ferrule and handle may be reversed with relation to the brush to insure even wear of the fiber, and which can be bodily removed from the brush when 35 the same is worn out, and readily applicable to a new brush; thus saving the ferrule, which under present practice is discarded and wasted when the brush is worn out.

Referring to the accompanying drawings: 40 Figure 1, is a perspective view of a brush constructed in accordance with this invention:

Fig. 2, is a longitudinal sectional view.

Fig. 3, is a transverse sectional view.

45 Fig. 4, is a detailed perspective view of the brush-block, metal cap and ferrule.

Fig. 5, is a diagrammatic view illustrating the manner of distributing the brush fiber on the brush-block.

50 Fig. 6, is a side elevation of the same, and Fig. 7, is an end elevation of the same, and

Fig. 8, is a longitudinal sectional view

through the brush and form for forming the brush material and for retaining the same in proper relation to the metal cap while said cap is being secured on the brush.

In the drawings, 1 indicates the brush, 2 the brush-block, 3 the metal cap, and 4 the handle-ferrule. 5 indicates the side-brush fiber, and 6 the end-brush fiber.

The brush-block 2 in this type of brush is elongated as shown, and in my construction the top-end portions of the block are stepped or depressed, as at 7, resulting in 65 the formation of shoulders 7^a, the purpose of which will appear later.

In the construction of the brush, a form 8 is employed which receives the metal cap 3 as shown in Fig. 8. The side-brush material 5 is placed across the form 8 (Fig. 5) and the end-brush-fiber 6 is wrapped with wire 9, and nailed to the block 2, said end-fiber 6 lying within the depressions 7 in the top face of the block (Fig. 6). When in 75 this position, the block 2 is forced into the form, or reversely, the form may be pressed over the block 2 and fiber 5 and 6. In either instance, the form 8 folds the side-fiber 5 down against the sides of the block as shown 80 in Fig. 5, and simultaneously folds the end-fiber 6 over and around the ends of the block, (Fig. 8) so as to distribute the end-fiber evenly and insure full ends to the brush.

When the brush is fully within the form 85 8, as shown in Fig. 8, the metal cap 3 is nailed to the block 2 through openings or spaces provided in the form; thus securing the cap on the brush so that upon removal from the form, the brush is in finished condition.

The ferrule 4 is constructed of two pieces of sheet metal 4' and 4'' riveted together at 10, the respective members having vertical portions 11 and 12 which straddle the brush 95 1, said portions as well as the brush being provided with complementary bolt-holes to receive removable bolts 13. The member 4' of the ferrule is formed to provide a socket 14 to receive a brush-handle 14' as shown. 100

By this construction the ferrule 4 may be reversed from time to time in relation to the brush in order to insure even wear of the fiber, and consequent efficiency and long life, while this also provides for the entire removal of the ferrule and bolts for applica- 105

tion to a new brush when the original brush has been discarded, thus effecting a very material saving.

What I claim as new and desire to secure 5 by Letters Patent of the United States, is:

A brush of the type described, including a fiber-equipped block adapted for the attachment of a handle thereto, said block provided with longitudinal depressions, in 10 its top-end portions, longitudinally disposed fiber layers embedded and secured in said depressions with their inner ends abutting the resulting shoulders thereof, said fiber layers extending downwardly along the 15 ends of said block and forming the end portions of the brush, additional fiber layers ex-

tending across the top of said block and overlying the upper surface of said end-forming brush portions and extending downwardly of said block and forming the 20 lateral brush portions in continuation of said end brush-forming portions, and a metal cap receiving said block and the upper portions of said end and lateral fiber layers and secured thereover.

In testimony whereof, I affix my signature, in presence of two witnesses.

SAMUEL B. McHENRY.

Witnesses:

ADELAIDE L. FERRIS,
MARGARET K. JACOBS.
